UNITED STATES PATENT OFFICE

WALTER H. HUTH AND BYRON B. MINNIUM, OF CHICAGO, ILLINOIS, ASSIGNEES TO
STORY & CLARK RADIO CORP., OF CHICAGO, ILLINOIS, A CORPORATION OF DELA-
WARE

RADIORECEIVING LOUD SPEAKER

Original application filed October 9, 1928, Serial No. 311,399. Divided and this application filed September 15, 1930. Serial No. 481,862.

This invention relates to radio loud speakers, and more particularly to electrostatic reproducers. This, therefore, is a division of our prior application, Serial No. 311,399, filed October 9, 1928.

Generally stated, the object of the invention, covered by this divisional application, is to provide a novel and improved construction whereby a vibratory member is supported in electrostatic relation to a stationary member, with a plurality of yielding supports interposed between the two members, distributed over the opposing surfaces thereof, whereby the vibratory member is normally held a distance from the opposing surface of the stationary member, but may vibrate freely when included in a radio or other reproducing circuit.

It is also an object to provide certain details and features of construction and combinations tending to increase the general efficiency and the desirability of a reproducer or loud speaker of this particular character.

To these and other useful ends, the invention consists in matters hereinafter set forth and claimed and shown in the accompanying drawings, in which—

Fig. 1 is a front or face view of a radio loud speaker or static reproducer embodying the principles of the invention;

Fig. 2 is a section on line 2—2 in Fig. 1;

Fig. 3 is a fragmentary enlarged section on line 3—3 of Fig. 1.

As thus illustrated, the invention comprises a stationary member or solid plate 1, having openings or perforations 2 therein. The outer surface of this plate is preferably insulated at 3 in any suitable or desired manner, providing a dielectric surface. This plate has a central support 4 by which it may be advantageously supported in any desired position.

The vibratory metal plate 5 is spaced a distance from the dielectric surface by the springs 6, formed of struck-out portions of said vibratory plate, bent toward the stationary plate, so that the ends of these springs or resilient supports engage and bear upon the dielectric surface. In this

way, the vibratory diaphragm or member 5 is provided with openings 7 therein, as shown.

The diaphragm 5 is held at its periphery by a ring 8, which in turn is mounted on springs 9 carried by the stationary member 1, previously mentioned, whereby the peripheries of the member 1 and the diaphragm 5 are substantially close together.

In this way, capacity is formed, substantially like an ordinary condenser, and when the member 1 and the diaphragm 5 are connected in series in a reproducing circuit, the charging action of the capacity will cause the desired vibration of the diaphragm 5, audibly, thereby providing a radio or other loud speaker operating on the electrostatic principle.

The springs 6 can be under some tension, so that when the diaphragm 5 moves away from the member 1, the ends of these springs will not be disengaged from the dielectric surface.

If necessary or desirable, the diaphragm 5 can be polarized by including it in a polarizing circuit (not shown) of any suitable character, so that the diaphragm will be under tension other than that caused by the reproducing circuit currents.

In this way, stationary and vibratory members are held in spaced relation, forming, in effect, a condenser or capacity, with yielding or resilient supports or spacing means interposed between said members, and are distributed over the opposing surfaces of said members, of such character as to maintain the desired separation between the two members, but without interfering with the free vibration of one member relatively to the other, by the charging and discharging action of the condenserlike structure or capacity thus formed, when the device is included in a reproducing circuit. The vibratory member 5 may be of any suitable flexible or resilient metal, or combination of metal and other materials. Regardless of the materials employed, however, it will be seen that the openings 2, and also the openings 7, provide for free circulation or flow of the air during the time that the

vibratory member 5 is in action, so that the air will not interfere with such vibratory action.

What we claim as our invention is:

- 5 1. An electrostatic reproducer comprising a stationary member and a vibratory member disposed a distance apart, with a plurality of yielding and resilient supports interposed between the two members, distributed over the opposing surfaces thereof, said members being adapted to be included in series in a reproducing circuit to cause audible action thereof by the vibration of said vibratory member.
- 10 15. 2. A structure as specified in claim 1, said supports being integral with said vibratory member.
- 15 20. 3. A structure as specified in claim 1, said vibratory member having an opening therein adjacent to each of said supports.
- 20 25. 4. A structure as specified in claim 1, said vibratory member comprising a resilient metal plate having springs formed integral- ly therewith, forming said supports.
- 25 30. 5. An electrostatic reproducer comprising means forming capacity having a resiliently supported and vibratory element adapted and operative to be vibrated audibly without rattling contact at intermediate rigid supporting points with any parts of the structure by the charging and discharging action of said capacity when connected in the reproducing circuit, comprising a sta- tionary or fixed plate, and a movable plate
- 30 35. forming said vibratory element, the movable plate having yielding spring support on the fixed or stationary plate, the spring support comprising a plurality of springs formed by metal struck out from the movable plate
- 35 40. 40 to provide perforations in the movable plate.
- 40 45. 6. An electrostatic reproducer comprising means forming capacity having a vibratory element adapted and operative to be vi- brated audibly by the charging and discharg- ing action of said capacity when connected in the reproducing circuit, comprising a sta- tionary or fixed plate, and a movable plate forming said vibratory element, the movable plate having yielding spring support on the
- 45 50. fixed or stationary plate, the spring support comprising a plurality of springs formed by metal struck out from the movable plate to provide perforations in the movable plate.

Specification signed this 3rd day of Sep-
tember, 1930.
